UNITED STATES PATENT OFFICE.

THOMAS L. VAN GIESSEN, OF LEECHBURG, AND DANIEL F. FOX, OF PITTSBURGH,
PENNSYLVANIA.

WIND-SHIELD CLEANER.

1,281,973.

Specification of Letters Patent. Patented July 3, 1917.

Application filed April 18, 1917. Serial No. 163,060.

To all whom it may concern:

Be it known that we, THOMAS L. VAN GIESSEN and DANIEL F. FOX, citizens of the United States, residing at Leechburg and Pittsburgh, respectively, in the counties of Armstrong and Allegheny and State of Pennsylvania, have invented certain new and useful Improvements in Wind-Shield Cleaners, of which the following is a specification, reference being had to the accompanying drawings.

This invention relates to new and useful improvements in window cleaners and more particularly to a cleaner for wind shields on automobiles, and the primary object of the invention is to provide a simple and efficient device of this character which is removably applied to the wind shield when desired and which is operable readily from the driver's seat.

A further object of the invention resides in providing a device which is adapted to be retained to the outer face of the wind shield by means of suction and which is operable in a horizontal plane across the glass, and a still further object resides in so constructing the device as to utilize the suction member as a wiper or cleaner for the glass.

Still another object resides in providing a device which is simple and durable in construction, inexpensive to manufacture and one which will be efficient and useful in operation.

With these and other objects in view our invention consists in the novel features of construction, combination and arrangement of parts, as will be hereinafter referred to and more particularly pointed out in the specification and claims.

In the accompanying drawing, forming a part of this application:—

Figure 1 is a perspective view of a wind shield showing a device constructed in accordance with our invention and applied to use thereon;

Fig. 2 is a side elevation of the device removed; and

Fig. 3 is a longitudinal section thereof, parts being shown in elevation.

In describing the invention, we shall refer to the drawings in which similar reference characters designate corresponding parts throughout the several views, and in which 55 1 designates a wind shield of the usual or

any preferred type, the glass therein being designated as 2. Our invention contemplates the provision of a member which can be quickly and readily applied and removed when desired.

To this end we provide a cleaner comprising a spring arm 3, which, as shown in the drawing, is constructed of wire, but which may be formed of any other desired material, the same having portions adjacent its end bulged or convexed, as shown at 4 to aid in the resiliency. Secured to the end of this arm by means of soldering, welding or any other methods, are the frames or bars 5 which carry the wipers 6, these wipers being preferably rubber. Formed integral with or otherwise secured to the central portion of the arm 5 is a concavo convex disk 7 to which is secured, by means of vulcanizing or otherwise, a rubber suction cup 8. The peripheral edges of this suction cup are beveled inwardly as shown at 9 and secured to the outer face of the disk 7 is a wire loop or the like 10 which projects on each side beyond the suction cup. Secured to the ends of the loop 10 are the flexible connections 11, such as chains or the like, the latter extending around the ends of the wind shield, in any manner, to be operated from the driver's seat.

When it is desired to use this device, the same is applied by forcing the suction cup against the outer face of the wind shield, such as any suction cup would be applied to a member, and the device will adhere thereto. The complete device may be drawn from one side to the other of the wind shield by drawing upon the flexible connections 11, and in view of the dampness on the glass 2, the device will readily slide thereover, the beveled edge 9 of the suction cup, preventing the inturn of the edges of the cup. The wipers 6 will clean the glass and it will be seen that the suction cup 8 will also form a wiper for the glass. Thus, the suction cup performs a double function in acting as a retaining means and a cleaning means. The device may be allowed to remain on the wind shield as long as desired and readily removed by the driver when no further use is desired therefor.

From the foregoing, it will be seen that we have provided a simple, inexpensive and efficient means for carrying out the objects of the invention, and while we have par-

ticularly described the elements best adapted to perform the functions set forth, it is obvious that various changes in the form, proportion and in the minor details of construction may be resorted to without departing from the spirit or sacrificing any of the principles of the invention.

Having thus described our invention, what we claim and desire to secure by Letters Patent is:—

10 1. A cleaner of the class described, comprising an arm, cleaning members carried thereby, and a suction member also carried by the arm to slidably retain the same to the member to be cleaned.

15 2. A cleaner of the class described, comprising a spring arm, wipers carried at the ends thereof, a suction member carried by the arm intermediate of said wipers and means for manually actuating said cleaner.

20 3. A cleaner of the class described, comprising a spring arm, wiping members carried at the ends thereof, a concavo convex

disk carried by the intermediate portion of said arm, a suction cup secured to said disk 25 and means for manually actuating said cleaner.

4. A cleaner of the class described, comprising a spring arm, wiping members carried at the ends thereof, a concavo convex 30 disk carried by the arm intermediate of said wiping members, a suction cup secured to said disk, and flexible connections extending from said disk to afford actuating means for the cleaner.

35 In testimony whereof, we hereunto affix our signatures in the presence of two witnesses.

THOMAS L. VAN GIESEN.
DANIEL F. FOX.
